UNITED STATES PATENT OFFICE.

JOHN KREHBIEL, OF CLEVELAND, OHIO, ASSIGNOR TO THE AMERICAN MACHINERY COMPANY, OF CLEVELAND, OHIO, A CORPORATION OF OHIO.

CAR-VESTIBULE.

No. 851,945.

Specification of Letters Patent.

Patented April 30, 1907.

Application filed June 30, 1906. Serial No. 324,142.

To all whom it may concern:

Be it known that I, JOHN KREHBIEL, a citizen of the United States of America, residing at Cleveland, in the county of Cuyahoga and State of Ohio; have invented certain new and useful Improvements in Car-Vestibules, of which the following is a specification, reference being had therein to the accompanying drawings.

10 This invention relates to improvements in vestibules for railway cars, and more especially to vestibules for electric or similar cars used in trains upon interurban and other roads where short turns and curves are frequent and where it would be impossible to use vestibule trains as ordinarily constructed owing to such turns.

One of the objects of the invention is to provide a very flexible connection between 20 the vestibule and car and to so pivotally connect the two that in going around a sharp turn the vestibule may swing quite a distance laterally to prevent breaking its connection with the vestibule of the next car and 25 may more closely follow the curve of the track.

It is also an object of the invention to so construct the vestibule as to form a closed compartment connected to the body of the 30 car by an unobstructed passage the width of which is not affected by the swinging of the vestibule and which vestibule and body by being so pivotally connected and arranged form a jointed car.

35 A further object of the invention is to provide means for hanging the bellows connection which will prevent wearing and cracking of the leather and to provide certain other new and useful features in the construction, 40 arrangement and combination of parts, all as hereinafter more fully described reference being had to the accompanying drawings, in which

Figure 1, is a side elevation of one end of a 45 car embodying the invention; Fig. 2, a horizontal section of the same; Fig. 3, a transverse section; and Fig. 4, a detail showing a portion of the car in longitudinal section.

1 is the body of the car having a roof portion 2 projecting beyond the body and forming a cover for the closed in vestibule 3 which is supported upon the supporting platform 4 projecting from the end of the car body. Beneath this platform is the car truck 5 pivot-

ally attached thereto by a king bolt 6 extending through the platform, and the floor of the vestibule is formed with a projecting semi-circular portion 7 through the axis of which the bolt 6 projects to pivotally attach the vestibule to the car body. From the base of the semi-circular projection the edge of the vestibule floor extends outward at an angle thus leaving an open space 8 at each side of the projection, between the end 9 of the car body and the inwardly slanting walls 10 of the vestibule which walls meet the side walls 11 at an obtuse angle and form a walled in compartment having a door 12 in one side and an open end 13 adapted to be secured in any desired manner to the open end of the 70 vestibule of the next car.

The space 8 is filled and closed to exclude the dust, dirt etc, by a bellows connection 14 between the walls 9 and 10. The loop portions or folds 15 of the bellows are formed of strips of flexible material and the inner edges of these strips are secured between the outer edges of strips of sheet metal 16 each folded longitudinally upon itself with a vertical rod 17 inclosed and secured in its inner looped end, which rods project upwardly and downwardly beyond the ends of the sheet metal. The upper ends of said rods are bent to form hooks 18 to hook over a semi-circular supporting track 19 carried by the vestibule to 85 turn therewith and supported concentric with the axis of the pivot thereof or the king bolt, and the lower projecting ends of said rods engage the inner side of a similar track 20 secured to the vestibule floor concentric with the semi-circular portion thereof and at a short distance outside the edge of said portion. The lower ends of the sheet metal loops 16 rest and slide upon the lower track and the bellows are thus supported and guided and 90 the flexible material protected and prevented from cracking. Shields of sheet metal 21 are secured to the outer surface of the side walls of the vestibule and project over the space 8 at the outer side of the bellows to protect and form a wind shield for the bellows and a vertical wall connecting the inner end of each wall 10 with the end of the car body to form the passage 22 leading from the car into the vestibule, is formed of a curtain 23 of suitable flexible material secured at one end to the inner end of the wall 10 and at its opposite end wound upon a suitable vertically

extending spring actuated roller 24. Shields 25 secured to the wall 9 of the car body form a casing for the rolls and also form a casing for the door leading from the car into the passage 22 the floor of which is made level by extending the car floor into said passage and forming it to fit the curve of the projection 7. The drawbar 26 is preferably pivoted upon the king bolt 6, and thus in going around a 10 curve in the track, the draw bar, truck and vestibule all turn upon the same center, the draw bar and vestibule turning together.

By pivoting the truck and vestibule upon the same center, the vestibule is permitted to 15 follow as nearly as possible, the curve of the railway track and thus a vestibule train of long cars may be run upon a track having short turns and curves, and the pivot being in the center of the passage 22, said passage 20 will not be narrowed by the turning of the vestibule. As the vestibule turns upon its pivot the curtain at one side of the passage will be unwound from its roll a short distance and the curtain at the opposite side 25 will be automatically wound upon its roll by the action of the coil spring which turns said roll in one direction, and the curtains are thus drawn taut at all times.

Having thus fully described the invention, 30 what I claim is:—

1. The combination with a car body and a truck at one end of said body to support the same, of a vestibule and a king bolt to pivotally attach the truck and vestibule to the 35 body.

2. The combination with a car body, of a supporting platform extending from one end of said body, a truck beneath said platform to support the car and pivotally attached 40 thereto, a vestibule supported by and pivotally attached to the platform and a king bolt extending through the floor of the vestibule, through the platform and through the bolster of the truck to pivotally connect the vestibule and truck to the car to turn upon a common pivot.

3. The combination with a car body, of a supporting platform extending from one end of said body, a truck beneath the platform, 50 a vestibule supported upon the platform and having a center pivot bearing adjacent to the end of the body, and a vertical pivot bolt extending through said bearing and through the platform and bolster of the truck.

4. The combination with a car body, of a vestibule pivotally attached to the end of the body in the longitudinal center line thereof and with a space between the end of the body and the vestibule to permit said vestibule to 55 turn on its pivot, side walls for the vestibule, and yielding means connecting said side walls and the end of the body to close said space.

5. The combination with a car body, of a vestibule pivotally attached to the end of the 60 body in the longitudinal center line thereof

and provided with a portion formed concentric with said pivot, and a projecting portion on the car body formed to conform to the curve of the concentric portion of the vestibule.

6. The combination with a car body, of a vestibule, a longitudinally extending semi-circular portion on one end of the floor of the vestibule forming a passage connecting the car body and vestibule, a vertical pivot located in the axis of said semi-circular extension for pivotally attaching the vestibule to the body, and flexible walls connecting the body and vestibule and extending along the sides of said extension to form the side walls 75 of said passage.

7. The combination with a car body having a pivot bearing at one end and a truck beneath said end to support the body, of a vestibule having a pivot bearing concentric 85 with the bearing on the body and the pivot bearing of the truck, a bolt engaging the bearings therefor in the vestibule body and truck, and a draw bar pivoted upon said bolt.

8. The combination with a car body, of a vestibule having a longitudinally extending semi-circular extension at one end, a pivot in the axis of said extension to attach the vestibule to the body, rigid walls on the vestibule extending from the base of said extension 95 outward, a flexible wall at each side of said extension connected at one end to the body and at the opposite end to the inner ends of the rigid walls, and means for yieldingly holding said yielding walls drawn taut.

9. The combination with a car body, of a vestibule pivotally attached to one end of said body with a space at each side of said pivot between the body and vestibule, fixed vertical side-walls for the vestibule, vertical 105 flexible walls attached at one end to the fixed walls and forming a passage from the car body to the vestibule, and spring actuated rollers carried by the body to which rollers the opposite ends of the flexible walls 110 are secured.

10. The combination with a car body and a vestibule attached thereto with a space between, of a bellows within the space to close the same consisting of folds of flexible material, rods secured in the inner loops of said folds and projecting therefrom at each end, and tracks to engage the projecting ends of said rods and guide and support the folds.

11. The combination with a car body and a vestibule attached thereto with a space between, of a bellows within the space consisting of outer folds formed of strips of flexible material, loops of sheet metal secured to the inner edges of said strips, and tracks to guide 115 and support the upper and lower ends of said loops.

12. The combination with a car body and a vestibule attached thereto with a space between, of a bellows within the space consist- 120

ing of outer folds formed of strips of flexible material, strips of sheet metal each folded longitudinally upon itself to form loops with the edges of the flexible strips secured within the loops, rods secured within the inner closed ends of the loops and bent at their upper ends to form hooks, and tracks engaged by the ends of said rods.

13. The combination with a car body, of a vestibule, a semi-circular portion on said vestibule with a space at each side thereof between the body and vestibule, a pivot bolt in the axis of said portion to pivotally attach the vestibule to the car body, bellows to fill said spaces consisting of folds of flexible material secured together and to the walls of the body and vestibule, vertical rods in the inner ends of the loops of said folds, and tracks engaged by the ends of the rods and secured to the vestibule and formed concentric with the semi-circular portion.

14. The combination with a car body, of a supporting platform extending from one end

of said body, a pivoted truck beneath the platform, a vestibule supported by the platform and formed with a semi-circular projection having an axial bearing, a king bolt engaging said bearing and extending through the platform and engaging the truck to pivotally attach the truck and vestibule to the body, a draw-bar pivoted on said bolt, a projection on the end of the car body formed to conform to the curve of the semi-circular portion of the vestibule and together with said portion forming a floor for a passage leading from the body to the vestibule, vertical walls on the vestibule extending inward to the base of the semi-circular portion, and bellows connecting the end of the body and said walls.

In testimony whereof I affix my signature in presence of two witnesses.

JOHN KREHBIEL.
